PROTECTED BINDING POST

Walter C. Hasselhorn, Chicago, Ill., assignor to
 Cook Electric Company, Chicago, Ill., a corpora-
 tion of Illinois

Application August 30, 1951, Serial No. 244,361

15 Claims. (Cl. 313—51)

1

This invention relates to a binding post structure and more particularly to a structure of this type to which a unitary lightning arrester may readily be connected.

It is an object of this invention to provide in a binding post structure a simple and inexpensive form of arrester protection which may be readily adopted and put into use in already existing installations without requiring additional expensive equipment and which will give the proper protection against sudden surges of high-potential currents. While the arrester unit is simple and easy to install, it will be understood that it also has equal utility in new installations and uses, as will readily appear.

A further object of the invention is to provide a binding post structure that may be readily mounted in position on its support and receive a detachable arrester unit, which, when in place on the binding post, will bring one of its electrodes in conducting relation in the line and will ground the other of its electrodes to the support.

A still further object of the invention is to provide a structure of the foregoing type which contains a few simple parts easily assembled and capable of being maintained in operating condition over long periods of time. The mounting structure for the binding post readily receives the arrester unit in detachable relation so that the arrester unit may be replaced without requiring any disturbance of the binding post parts or the service on the line.

A still further object of the invention is to provide a mounting for a binding post which includes a few simple parts that detachingly hold the binding post to its support, these parts comprising a shank preferably extending through the support and insulated therefrom and an arrester-carrying member in the form of a housing, there being an insulation member carrying one of the terminals of the binding post and providing the ready means for affording a connection with one of the electrodes of the arrester unit. This insulation part may be molded with the terminal embedded therein, or otherwise associated therewith, so that a line connection may be conveniently made therewith.

Other objects and advantages of the invention will be apparent from the following detail description when taken in connection with the accompanying drawing which forms a part hereof.

In the drawing:

Figure 1 is a transverse section of a structure embodying the invention; and

Fig. 2 is a slightly modified form thereof.

2

As illustrated in the drawing, a structure embodying the present invention may include a mounting or a support 2 on which binding post 3 is mounted. Binding post 3 may be of any design with its projecting outer end functioning as a terminal to which a line conductor may be attached. This binding post will preferably have a shank 4 extending through an opening 5 in support 2. Shank 4 may be internally threaded as at 6 to receive a bolt 7, there being a metal washer 8 carried by bolt 7 for holding an insulation member 9 in position. The upper end of insulation member 9 is stepped inwardly and upwardly so that a neck 10 thereof extends into opening 5 of support 2 and keeps shank 4 centered in this opening 5 and in insulated relation with respect to support 2. A washer or collar 11 of insulation material is disposed between base 12 of binding post 3 and support 2.

Insulation member 9 is preferably in concentric relation to shank 4. It may have the other terminal 14 of the line suitably carried thereby and provided in electrical conducting relation with shank 4 of binding post 3 through, say, a metallic sleeve 15 engaging washer 8 and bolt 7 threaded into shank 4. It is found that an exceptionally novel assembly design operating very effectively in the present arrangement may be had if terminal 14 and sleeve 15 are embedded in insulation member 9 during the molding of the latter. As illustrated, insulation member 9 may have an extension 16 for lending added support to terminal 14. Terminal 14 may be connected to sleeve 15 by a grooved joint as shown, but any other suitable connection will serve the purpose.

A housing or enclosure member 18 surrounds the insulation member 9 and it is held in attached relation to support 2 by an inwardly turned flange 19 seated against the outermost step of insulation member 9. It is found that insulation member 9 may be uniquely formed in housing 18 during the molding thereof by placing this housing and terminal member 14 in the cavity of the mold and causing the insulation material to flow about the terminal member and into the form of this insulation member. Thus, insulation member 9 will be embedded in housing 18 and terminal member 14 will be embedded in this insulation member. Extension 16 may be easily formed and keep terminal member 14 insulated from housing 18.

It will be apparent that securing threaded bolt 7 into position will clamp the parts thus described into position against support 2 and complete the line circuit through binding post 3 to

terminal 14, the head of bolt 1 also remaining in conducting relation in this line circuit. The arrangement of these parts allows for simple and effective arrester protection by the use of an arrester unit 22 adapted to be detachably connected to housing 18. The arrester unit 22 is preferably of the button type and includes a cup-shaped housing 24 having an externally threaded portion 25 for engagement with a threaded portion 26 of housing 18. Housing 24 is adapted to receive a pair of carbon blocks 27 and 28 held apart at a predetermined distance to form spark gap 29 by a suitable dielectric member 30. Dielectric member 30 is in the form of a ring having its inner edge 31 disposed within grooves 32 in carbon blocks 27 and 28, these grooves 32 acting to collect particles disintegrating from carbon blocks 27 and 28 as the result of sparking across gap 29 and heretofore tending to collect at edge 31. Carbon blocks 27 and 28 and dielectric member 30 are held centered and in assembled relation by an insulation sleeve 33 having a top flange 34 holding spring members 35 between carbon block 28 and base 36 of electrode 37. Insulation sleeve 33 is maintained in position, say, by a split ring 38 that may be seated in a groove 39 cut in the inside face of housing 24.

When arrester unit 22 is detachably fastened in position by threading housing 24 in engaging relation with housing 18, electrode 37 of arrester unit 22 will be brought firmly into electric conducting relation with bolt 1, a slight pressure being maintained by reason of spring members 35 which also keep carbon blocks 27 and 28 firmly pressed together with dielectric member 30 therebetween whereby to maintain spark gap 29 of a predetermined distance. A sudden surge of high-potential current will jump the gap 29 and be grounded through housing 24 and housing 18 to the grounded support 2.

Housings 18 and 24 provide a closure that effectively prevents accumulation of dirt and other foreign matter and also prevents moisture from reaching the carbon blocks 27 and 28 to destroy or reduce the effectiveness of spark gap 29. The arrangement is exceptionally simple because housing 24 effectively acts as the second electrode for arrester unit 22 to ground current surges through housing 18 directly to grounded support 2. Thus, housing parts 18 and 24 serve the dual purpose of effectively enclosing the parts of the assembly, both of the binding post and of the lightning arrester, and of acting as adequate grounding members for the current surges when they occur and jump the spark gap 29.

A modified form of structure is shown in Fig. 2. Binding post 3 has its shank 4 passing through opening 5 in grounded support 2. Shank 4 is held centrally spaced and in insulated relation with grounded support 2 by insulation member 40 having an upstanding flange 41 surrounding shank 4 and lying in opening 5. Insulation member 40 is likewise provided with an extension designated 42 to receive terminal 43 embedded in insulation member 40. Housing 44 surrounds insulating member 40 and holds the latter in position when bolt 45 is threaded into position in shank 4. In this instance, bolt 45 may have an enlarged head with an upstanding shoulder 46 seated in a central cut-away portion 47 in insulation member 40. The line circuit is completed through shank 4 by shoulder 46 bearing against terminal member 43. Terminal member 43 is also molded in member 40 as illustrated in the drawing.

Lightning arrester unit 48 is constructed substantially the same as arrester unit 22. The parts of the arrester unit, such as the carbon blocks, the dielectric spacing ring, the spring member and the inner electrode may be assembled within a casing 50 preferably at the factory to assure the maintenance of a predetermined spark gap between the carbon blocks. If, for any reason, it should be desirable to remove these parts of the arrester unit, this sub-assembly within casing 50 may be removed and a new assembly inserted in housing 51 without interrupting the service on the line.

While the housing of the arrester unit is shown in both embodiments as being attached to the binding post assembly by a threaded connection, it will be obvious that any suitable readily detachable connection may be used without departing from the scope of the invention. Also, while both the housing of the binding post and the housing of the arrester unit very effectively act as an enclosure for the parts of this binding post, it will be understood that current surges may be grounded through any other part to the part carried in grounded relation with support 2.

Without further elaboration, the foregoing will so fully explain the gist of my invention that others may, by applying current knowledge, readily adapt the same for use under varying conditions of service, without eliminating certain features, which may properly be said to constitute the essential items of novelty involved, which items are intended to be defined and secured to me by the following claims.

I claim:

1. In combination, a binding post assembly, a grounded mounting for the same, said binding post assembly comprising a post having a terminal connection on one side of said mounting and a shank extending through said mounting to the other side thereof, insulation means carried by said shank, a second terminal connection carried by said insulation means, means for bringing said second terminal in electrical conducting relation with said shank, a conductor member held by said last means in electrical conducting relation with said grounded mounting; and an arrester forming a part of said assembly, one electrode of said arrester being in electrical conducting relation with said last means, the other electrode of said arrester constituting the attaching means of said arrester and being secured to said conductor member.

2. In combination, a binding post, a grounded mounting for the same, said binding post comprising a terminal post extending through said mounting from one to the other side, means for locking said terminal post in position, said means including an insulating part, an electrical conducting part and a threaded connecting part, said threaded connecting part holding all said parts in assembled relation on one side of said mounting with said conducting part secured to one said side of said mounting and said terminal post centered in insulated relation with said mounting, and an arrester carried by said assembled parts, said arrester including an electrode in electrical relation to said terminal post and a second electrode in electrical relation to said conducting part.

3. In combination, a binding post, a grounded mounting for the same, said binding post comprising a terminal post extending through said mounting from one to the other side, means for locking said terminal post in insulated relation

with said mounting, said locking means including an insulated part, an electrical conducting part and a mechanical fastening part, and an arrester carried by said parts including an electrode in electrical relation to said terminal post and a second electrode in electrical relation to said grounded mounting through said conducting part.

4. In combination, a binding post, a grounded mounting for the same, said binding post extending in insulated relation through said grounded mounting, terminal connections for said binding post on opposite sides of said grounded mounting, a conductor part in electrical conducting relation with said grounded mounting, an insulated part separating one of said terminal connections from said conductor part, a fastening part for holding said one terminal connection, said insulated part and said conductor part in position against said grounded mounting but with said one terminal connection in electrical relation with said binding post, and an arrester carried by said parts, said arrester having an electrode in electrical relation to said binding post and an electrode in electrical relation to said grounded mounting.

5. In combination, a binding post, a grounded mounting for the same, said binding post extending in insulated relation through said grounded mounting, terminal connections for said binding post on opposite sides of said grounded mounting, an arrester carried by said binding post on one side of said grounded mounting, said arrester including an electrode in electrical conducting relation with said binding post, an electrode in electrical conducting relation with said grounded mounting, and a detachable connecting member having means for detachably connecting said arrester to said binding post.

6. In combination, a binding post, a grounded mounting for the same, said binding post extending in insulated relation through said grounded mounting, terminal connections for said binding post on opposite sides of said grounded mounting, an arrester carried by said binding post on one side of said grounded mounting, said arrester including an electrode in electrical conducting relation with said binding post, an electrode in electrical conducting relation with said grounded mounting, a detachable connecting member having means for detachably connecting said arrester to said binding post, and an insulation part for keeping one of said terminal connections in insulated relation with said grounded connection.

7. In combination, a binding post, a grounded mounting for the same, said binding post extending in insulated relation through said grounded mounting, terminal connections for said binding post on opposite sides of said grounded mounting, an arrester carried by said binding post on one side of said grounded mounting, said arrester including an electrode in electrical conducting relation with said binding post, an electrode in electrical conducting relation with said grounded mounting, a detachable connecting member having means for detachably connecting said arrester to said binding post, and an insulation part for keeping one of said terminal connections in insulated relation with said grounded connection, said last terminal connection being embedded in said insulation part.

8. In combination, a binding post, a grounded mounting for the same, said binding post ex-

tending in insulated relation through said grounded mounting, terminal connections for said binding post on opposite sides of said grounded mounting, an arrester carried by said binding post on one side of said grounded mounting, said arrester including an electrode in electrical conducting relation with said binding post, an electrode in electrical conducting relation with said grounded mounting, a detachable connecting member having means for detachably connecting said arrester to said binding post, and an insulation part for keeping one of said terminal connections in insulated relation with said grounded connection, said last terminal connection being embedded in said insulation part, there being means to bring said last terminal connection in conducting relation with said binding post.

9. In combination, a binding post, a grounded mounting for the same, said binding post extending in insulated relation through said grounded mounting, terminal connections for said binding post on opposite sides of said grounded mounting, an arrester carried by said binding post on one side of said grounded mounting, said arrester including an electrode in electrical conducting relation with said binding post and a second electrode in electrical conducting relation with said grounded mounting, said electrodes being adjustably supported in predetermined spaced relationship.

10. In combination, a binding post, line terminal connections for said binding post, a grounded mounting for said binding post, means for attaching said binding post to said mounting in insulated relationship, and an arrester for said binding post, said arrester having an electrode electrically connected to said binding post and an electrode detachably grounded to said mounting.

11. In combination, a binding post, line terminal connections for said binding post, a grounded mounting for said binding post, means for attaching said binding post to said mounting in insulated relationship, and an arrester for said binding post, said arrester having its electrodes electrically connected respectively to said binding post and to said mounting through said attaching means.

12. In combination, a binding post, a grounded mounting for the same, said binding post having a shank passing through said mounting, a grounded housing surrounding said shank, an insulation member disposed between said shank and said housing, a bolt secured to said shank to clamp said housing against said mounting and to hold said insulation member in position, and an arrester detachably secured to said housing to ground one of its electrodes through said housing to said mounting and to bring the other of its electrodes in abutting engagement with said bolt.

13. In combination, a binding post, a grounded mounting for the same, said binding post having a shank passing through said mounting, a housing surrounding said shank, an insulation member disposed between said shank and said housing, a fastening member secured to said shank to hold said parts in position, and an arrester detachably carried by said housing to ground one of its electrodes to said mounting and to electrically connect the other of its electrodes to said shank.

14. In combination, a binding post, a grounded mounting for the same, said binding post hav-

ing a shank passing through said mounting, a housing surrounding said shank, an insulation member disposed between said shank and said housing, a fastening member for securing said parts in position against said mounting, a terminal carried by said insulation member and being electrically connected to said shank, and an arrester having one of its electrodes abuttingly engaging said fastening member and the other of its electrodes grounded to said mounting.

15. In combination, a binding post, a grounded mounting for the same, said binding post having a shank passing through said mounting, a housing surrounding said shank, an insulation member disposed between said shank and said housing, a fastening member for securing said

parts in position against said mounting, a terminal embedded in said insulation member and projecting beyond said housing, said terminal being electrically connected to said shank, and an arrester having one of its electrodes abuttingly engaging said fastening member and the other of its electrodes grounded to said mounting.
